(57) **CLAIM**

The ornamental design for a portion of a light fixture, as shown and described.

DESCRIPTION

FIG. 1 is a perspective view of a first embodiment of a portion of a light fixture showing my new design;

FIG. 2 is a bottom view thereof;

FIG. 3 is a top view thereof;

FIG. 4 is a right-side view thereof, the left-side view being a mirror image;

FIG. 5 is a bottom view of a second embodiment thereof;

FIG. 6 is a top view thereof;

FIG. 7 is a right-side view thereof, the left-side view being a mirror image;

FIG. 8 is a bottom view of a third embodiment thereof;

FIG. 9 is a top view thereof;

FIG. 10 is a right-side view thereof, the left-side view being a mirror image;

FIG. 11 is a bottom view of a fourth embodiment thereof;

FIG. 12 is a top view thereof; and,

FIG. 13 is a right-side view thereof, the left-side view being a mirror image.

The broken lines are environmental and form no part of the claimed design.
